United States Patent Office.

C. L. HORACK, OF WILLIMANTIC, CONNECTICUT.

Letters Patent No. 96,808, dated November 16, 1869.

IMPROVEMENT IN BUTTONS.

The Schedule referred to in these Letters Patent and making part of the same.

To all whom it may concern:

Be it known that I, C. L. HORACK, of Willimantic, in the county of Windham, and State of Connecticut, have invented a new and useful Improvement in Stud and Button-Fastening; and I do hereby declare that the following is a full, clear, and exact description thereof, which will enable others skilled in the art to make and use the same, reference being had to the accompanying drawings, forming part of this specification.

This invention relates to a new and useful improvement in a device for fastening studs and buttons to shirt-bosoms and wristbands, and for all similar uses, whereby studs and buttons are well secured, and loss thereof prevented; and

The invention consists in the construction and arrangement hereinafter described.

In the accompanying drawing—

Figure 1 represents a cross-section through the line xx of fig. 2.

Figure 2 is a view of the under or reverse side of the stud or button.

Similar letters of reference indicate corresponding parts.

A is the button or plate, which may be in any form, and of any desired size, and made of any suitable material.

On the under side of the button, eccentrically, (or one side of the centre,) I attach a post, B; and to the outer end of the post B is rigidly attached an arm, C, reaching over the centre of the button, to near its rim or edge, as seen in the drawing.

D is a tube around the post B, confined between the under side of the button and the arm C, so that the same is free to revolve around the post.

To each end of this tube, on opposite sides, an arm is attached.

E is the arm on the outer end of the tube, and F is the arm on the inner end, which latter arm is in

contact with the under side of the button, and traverses over its surface as the tube is revolved on the post.

As seen in fig. 1, the button or stud is represented as fastened in the garment. The dotted lines, fig. 1, represent the cloth to which it is fastened.

On the under side of the button, there is a small projection; and in the inner side of the arm F, there is a cavity, both of which are seen at G.

The arm F is allowed to spring outward a little, so that the projection on the button will enter the cavity in the arm, by which means the arms E and F are held stationary, and the fastening is made complete.

It will be seen, that when thus fastened to the cloth or garment, the stationary arm C and the revolving or movable arm E extend from the post in opposite directions, so that, until the arm F is raised from the projection at G, the fastening is secure.

Before the stud or button is put in use, the position of the arms E and F is reversed. E is covered by C, as indicated in dotted lines in fig. 1. In this position, they are readily passed through the button-holes, when E and F are turned, as seen, and fastened, as before stated.

The advantages of this arrangement are, durability of the parts, and the security and safety of the button afforded thereby.

Having thus described my invention,

I claim as new, and desire to secure by Letters Patent—

In combination with the stud or button A, the post B, tube D, and arms C, E, and F, constructed, arranged, and operating substantially as and for the purposes described.

C. L. HORACK.
